UNITED STATES PATENT OFFICE.

EDMUND H. LUNKEN, OF CINCINNATI, OHIO.

WINDOW.

1,285,270.

Specification of Letters Patent. Patented Nov. 19, 1918.

Application filed April 5, 1918. Serial No. 226,802.

To all whom it may concern:

Be it known that I, EDMUND H. LUNKEN, a citizen of the United States, and a resident of Cincinnati, in the county of Hamilton and State of Ohio, have invented certain new and useful Improvements in Windows, of which the following is a full, clear, and exact description, reference being had to the accompanying drawing, forming part 10 of this specification.

My invention relates to what is known as pocket windows in which a pocket is provided in the upper portion of the sash frame for the reception of the sash to give a free 15 and unobstructed window opening. It is usual in pocket windows of the kind specified to also provide for window screens which are located outside the sash and adapted to be also pushed up into the window pocket to obtain free access to the sash. 20

My invention in this connection has particularly to do with pocket windows in which by reason of the height of the framework, or for any other cause, it is not practicable to provide a pocket to receive the 25 full length of the sash. The invention also has relation to a construction in which provision shall be made in the sash frame for window screens, but in which the screens if 30 desired may be omitted or removed without exposing an air opening around the sash. It is the object, therefore, of my present invention to arrange a construction in which the pockets for the window sash and for the 35 screens shall be entirely independent of each other and so that whether screens are used or not, no air opening shall exist around the sash by reason of the pocket construction.

The invention consists of that novel construction and arrangement of parts to be hereinafter specifically pointed out and claimed whereby this independence of the sash and screen pockets shall be obtained.

In the drawing,

45 Figure 1 is a vertical longitudinal section taken through a window embodying my invention, with the screens in place closing the window opening.

Fig. 2 is a similar longitudinal section of 50 the upper portion of the window showing the screens raised into the window pocket.

Fig. 3 is a cross section of the window frame taken on the lines 3-3 of Fig. 1.

The window pocket is provided with the 55 usual lower and upper sliding sashes 1 and

2, with the meeting rails 3, 4, the sashes being mounted in the side stiles 5, 6, with the inside and outside beads 7, 8, and the parting bead 9, with the sill 10 and head piece 11. The stiles run to the top of the pocket 60 above the window opening and the head piece incloses the pocket at the top, while the front of the pocket is in the construction illustrated formed of corrugated sheet metal 12 for the plastering 13, and the outer 65 wall of the pocket is inclosed by sheeting 14 over which the weatherboarding 15 for the outside structure in frame buildings is secured. The window casing is also provided with the usual inside and outside trims 16, 70 17. The wall pocket, which in the construction illustrated is say, of only three-quarters depth, is divided by the partition 18 into two independent pockets, front and rear, of a sufficient horizontal depth to receive the two sashes and two screens respectively. These screens are preferably formed of metal frames 19 for the lower, and 20 for the upper screen, with the wire screening 21 secured to the frames in any 75 suitable way. The lower screen is provided with a flanged strip 22 to engage over the lower rail of the upper screen, to form a close joint and to raise the upper screen when the two screens are pushed up into 80 the pocket, while the upper rail of the upper screen is provided of double thickness as shown at 23 to fill out the opening in the 85 guide way.

The partition 18 completely divides the 90 pocket, and the lower edge of the partition extends to the upper portion of the window opening, and this lower edge is provided with a U-shaped preferably metallic binding piece 24, which surface forms a contact piece for the weatherstrip 25, which is secured along the upper rail of the upper sash, and thus forms a tight weatherproof joint for the sash, and prevents the entrance 95 of air around the sash through the window 100 pocket. In addition this binding strip for the partition gives sufficient space between the partition and the parting bead for raising the upper sash into the pocket without binding.

To serve as a suitable runway and guide for the screens, I provide the U-shaped channel pieces 26, which are mounted on the side stiles and run from the bottom to the head of the pocket, and the upper rails of the 110

two screens have their side faces somewhat curved so as to provide an easy sliding contact in these guide channels, and at the same time sufficient frictional contact to maintain 5 the screens in raised position. The lower rail of the lower screen frame is also provided with an angle plate 27, the ends of which are guided in the side channels.

The sashes are provided with the usual 10 sash cords 28, which run over the sash pulleys 29 at the head of the pulley stile at the upper end of the pocket, and these cords are attached to the usual sash weights 30 in the weight box 31 behind the stiles.

15 With this construction of pocket window, with the sash and screen pockets independent, it is evident that the screens can be removed or entirely dispensed with, without in any way affecting the utility of the 20 sash pocket construction. A tight fitting weatherproof joint is provided for the weatherstrip on the upper surface of the upper rail of the upper sash. Secured in the screen channel by rivets or screws are 25 spring plates or strips 32 which bear against the sides of the screens and spring out to hold the screens up when raised beyond the ends of the plates and which are pressed in to release the screens. The upper screen is 30 held in its lowered position by similar springs 33 which engage a notch in the upper side edges of the screen frame on each side.

Having thus described my invention, what

I claim as new and desire to secure by Letters Patent, is:—

1. In a pocket window construction, a window frame and sash with runway for window screens therein, a wall pocket adjacent the window opening of a width to receive both of the sashes and the screens, and a partition to divide the pocket into independent sections, one for both sashes and the other for the screen. 40

2. In a pocket window construction, a window frame and sash with runway for window screens therein, a wall pocket adjacent the window opening of a width to receive both of the sashes and the screens, and a partition to divide the pocket into independent sections, one for both sashes and the other for the screen, with the upper rail of the upper sash bearing against the lower portion of said partition when the sashes are closed to make an air tight closure. 50

3. In a pocket window construction, a window frame and sash with runway for window screens therein, a wall pocket adjacent the window opening of a width to receive both of the sashes and the screens, and a partition to divide the pocket into independent sections, one for both sashes and the other for the screen, and a metallic binding for the lower edge of the partition, and a weatherstrip along the upper edge of the upper sash to engage therewith when the sash is closed, to form a weather joint. 60

EDMUND H. LUNKEN.
